Inventor:

Thos H. Hicks

UNITED STATES PATENT OFFICE.

THOMAS H. HICKS, OF DETROIT, MICHIGAN, ASSIGNOR TO MAX LOUIS ROSSVALY, OF SAME PLACE.

TENSION CHECK-SPRING.

SPECIFICATION forming part of Letters Patent No. 310,426, dated January 6, 1885.

Application filed October 9, 1884. (No model.)

To all whom it may concern:

Be it known that I, THOMAS HAMMILL HICKS, residing at the city of Detroit, in the county of Wayne and State of Michigan, physician, have invented certain new and useful Improvements on Tension Check-Springs, of which the following is a specification.

This invention relates to an improvement in tension check-springs; and the invention consists in the peculiar construction and arrangement of the parts, all as hereinafter described.

In the drawings, which accompany this specification, Figure 1 is a plan view of my improved device. Fig. 2 is a cross-section showing one of the two guide-plates in elevation.

This tension check-spring consists of the wire frames A and E, of the guide-plates H D, and of the coil-spring I.

The wire frame A consists of a single piece 20 of wire, bent in the manner shown to form the loops b b and the parallel guide-bars c c. The wire frame E also consists of a single piece of wire, bent in manner shown to form the loop f and the parallel guide-bars g g.

The guide-plate H is a metal plate riveted or otherwise secured to the ends of the guide-bars g g, while the guide-bars c c slide through suitable holes in this plate. The guide-plate D is riveted or otherwise secured to the ends 30 of the guide-bars c c, while the guide-bars g g pass loosely through suitable holes in this guide-plate.

I is a coil-spring of suitable tension interposed between the guide-plates D H, its coils 35 passing around the guide-bars g g.

L is a leather flap secured to the loop f, by means of which the device is hooked onto the usual check-rein hook of the saddle or harness.

In practice the device is equally applicable 40 to side or overhead check-reins, the ends K K of which have to be secured to the loops b b, as shown.

The advantage of my improved device is that it is strong and simple and not liable to 45 come apart accidentally, as there are two loops for attaching the check rein or reins. The latter can be so arranged that any interference with the horse's mane may be avoided.

Instead of one coil-spring, as shown, several 50 coil-springs may be interposed between the guide-plates D H, and kept in place by coiling them around one or more of the guide-bars.

What I claim as my invention is—

1. In combination, the frame A, having loops b b and parallel guide-bars c c, the frame E, having loop f and parallel guide-bars g g, the guide-plates D H, secured to the ends of the guide-bars of one frame and sliding loosely on the 60 guide-bars of the other frame, respectively, and a coil-spring, I, interposed between the guide-plates, substantially as described.

2. As an improved article of manufacture, a tension check-spring consisting of the frames 65 A E, bent of single pieces of wire, forming suitable loops for securing the device in place, guide-bars c c g g, guide-plates D H, secured to the ends of the guide-bars of one frame and sliding loosely on the guide-bars of the other frame, respectively, and the tension-spring I, 70 interposed between the guide-plates, all combined substantially as described.

THOS. H. HICKS.
